(57) **CLAIM**

The ornamental design for a circular saw bit for vibrating saw, as shown and described.

DESCRIPTION

FIG. 1 is a perspective view of a circular saw bit for vibrating saw;

FIG. 2 is a front view thereof;

FIG. 3 is a top view thereof;

FIG. 4 is a right-side view thereof;

FIG. 5 is a left-side view thereof;

FIG. 6 is a rear view thereof; and,

FIG. 7 is a bottom view thereof.
